UNITED STATES PATENT OFFICE.

MILON J. TRUMBLE, OF LOS ANGELES, CALIFORNIA.

DISTILLATION APPARATUS.

Application filed November 14, 1923. Serial No. 674,680.

To all whom it may concern:

Be it known that I, MILON J. TRUMBLE, a citizen of the United States, residing at Los Angeles, in the county of Los Angeles, 5 State of California, have invented a new and useful Distillation Apparatus, of which the following is a specification.

My invention relates to the art of distillation and more particularly to the production 10 of hydrocarbon oils from various raw materials.

There occur in nature many deposits which contain hydrocarbons, or which, like the shales, may be made to yield hydrocarbons if subjected to heat and pressure. 15 Such, for example, are the so-called oil sands which yield complex mixtures of hydrocarbons commonly and hereinafter termed "crude oil".

20 It is an object of my invention to provide an apparatus by which hydrocarbons of high commercial value can be cheaply produced from such crude oil or other materials containing hydrocarbons, all such materials 25 being hereinafter termed "raw materials".

I have found that where such raw material contains or is mixed with comminuted wood, straw, brown coal, lignite, or other material containing a large proportion of 30 woody fibre, (all such materials being hereinafter termed "ligneous material") that a molecular rearrangement of the hydrocarbons seems to take place upon the application of heat to the mixture, the result being 35 a complex mixture of hydrocarbon oils of high volatility and low specific gravity. Oils of this character are at the present time in great demand and their commercial value is high.

40 It is therefore a further object of my invention to provide means for distilling a mixture of raw material and ligneous material for the purpose of producing volatile hydrocarbons.

45 It is found that where raw material is distilled in fire stills, that is in closed vessels, to the exterior of which hot gases of combustion are applied, coking is liable to occur in the still due to local overheating. 50 This can be partially overcome by using steam as a heating agent, but unless superheated steam is employed the difference in temperature between the steam and the still contents is so low that unduly large stills 55 must be employed. I, therefore, employ

superheated steam internally applied to the still or treater through pipe coils. It is a further object of my invention to provide mechanical means for cleaning off any deposits which may form on the exterior surface of said coils. 60

The use of steam in steam coils placed in the still is old and has previously been considered uneconomical due to the large amount of heat required to convert water into steam, i. e. the latent heat of vaporization. Where steam is so used in the ordinary refining process, large quantities of fuel are burned to supply this latent heat of vaporization, this heat being afterwards removed from the vapors and steam in suitable condensers. It is a further object of my invention to provide means by which a considerable portion of the heat applied to the steam is recovered as mechanical 70 power. 75

Further objects and advantages will be made evident hereinafter.

In the drawings which are for illustrative purposes only, 80

Fig. 1 is an isometric diagram of apparatus adapted to carry on my process.

Fig. 2 is a cross section through a preferred form of still.

Fig. 3 is an isometric view of the tubes 85 and scraper of the still.

In the form of invention illustrated, I employ a battery of boilers 11, a battery of heaters 12, three stills 13, 14 and 15, two preheaters 16 and 17, a prime mover 18, a condenser 19, and a separator 20. 90

The boilers 11 are of conventional form and supply saturated steam through a pipe 25 to the heaters 12. The heaters 12 consist of closed vessels 26, 27 and 28 enclosed in a furnace 29, which is fired by a gas burner 30. The steam is superheated in the vessel 26 and is conducted through a pipe 31 to the first still or treater 13. The pipe 31 is joined as shown in Fig. 3 to two pipes 32, each of which projects into one of two large pipes 33. The pipes 33 project into the still 13 and are closed at their anterior end by caps 35. The anterior ends 36 of the pipes 32 are open and the steam is delivered therethrough into the anterior ends of the pipes 33. The pipes 33 are secured at their posterior ends in flanges 37 welded or otherwise secured in the shell of the treater 13. A pipe 40 is also secured in the pipes 33 110

and has secured thereto a pipe 41 which extends down and conducts the partially cooled steam to the second vessel 27.

In the vessel 27 the steam is again raised 5 in temperature, being delivered through a pipe 42 to a pipe corresponding to the pipe 32 in the second treater 14; the treaters 13, 14 and 15 being of identical construction. The steam after passing through pipes similar to 32 and 33 in the treater 14 is carried 10 by a pipe 43 to the third vessel 28, being again raised in temperature therein. Steam is then conducted from the vessel 28 through a pipe 44 into the third treater 15.

15 The partially cooled steam from the third treater 15 is conducted through a pipe 45 to one or the other of the preheaters 16 and 17, the pipe 45 having branches provided with valves 46 which may be used to direct 20 the steam into either of the preheaters 16 or 17.

The preheaters 16 and 17 are identical in construction and may be filled with comminuted ligneous material through removable 25 covers 50. Raw material, such as crude oil, is delivered through a pipe 51, having branches closed by valves 52, into either of the preheaters 16 or 17. Vapor is delivered from a main 55 through branches having 30 valves 56 into either of the preheaters 16 or 17. Each of the preheaters 16 and 17 has a pipe 57 having a valve 58, through which material from either of the preheaters may be delivered to the third still 15.

35 This material may be pulled from the posterior to the anterior end of each still by a scraper 60 mounted on the pipes 33 and actuated by a pull rod 61 which projects through a stuffing box 62 in the anterior end 40 of each still. The scraper 60 not only acts to pull solid material to the anterior end of each still but also serves to scrape off the outer surface of the pipes 33 any adhering solid matter. Material in the anterior end 45 of still 15 can be discharged into the posterior end of still 14 through a pipe 63 having a valve 64. Material in the anterior end of still 14 can be discharged into the posterior end of still 13 through a pipe 65 having a valve 66. Material in the anterior end of 50 still 13 can be discharged through a pipe 67 having a valve 68.

Excess liquid in still 15 discharges into 55 still 14 through a pipe 70 having a valve 71; excess liquid in still 14 discharges into still 12 through a pipe 72 having a valve 73; and excess liquid may be drawn off from still 13 through a pipe 74 having a valve 75.

60 Vapor outlets are provided for each still 13, 14 and 15. The vapor outlet 80 from still 13 discharges through a valve 81 with the main 55 or may be discharged through a valve 82 and an outlet pipe 83 to suitable condensers, not shown. The vapor outlet 85 from still 14 discharges through a valve 86

into the main 55, or through a valve 87 and an outlet pipe 88 to suitable condensers, not shown. The vapor outlet 90 from the still 15 discharges through a valve 91 into the main 55 or through a valve 92 into an outlet 70 pipe 93 to suitable condensers, not shown.

Vapor and steam may be delivered through valves 95 and a pipe 96 to the steam turbine 18, the exhaust therefrom passing through a pipe 97 to the condenser 19. Condensates are delivered through a pipe 98 to the separator 20, the water and water soluble salts being then delivered through a pipe 100 and the oil through a pipe 99 therefrom.

80 The method of operation is as follows:

The plant is designed to operate continuously, and when so operating the stills 13, 14 and 15 are filled with a mixture of raw and ligneous material.

85 In the stills 13, 14 and 15 this mixture is subjected to the heat of the steam in the pipes 33, this steam being superheated before being passed into each still by the heaters 26, 27 and 28. The cooled steam from the third still 15 is blown directly 90 into a mixture of raw and ligneous material in one of the preheaters 16 or 17. These preheaters are charged with oil from the pipe 51 and with ligneous material through the opening closed by the cover 50.

95 Vapors are produced in the stills 13, 14 and 15 and these vapors are either blown 100 into one of the preheaters 16 or 17 through the main 55, or are drawn off through one of the pipes 83, 88 or 93 and condensed. When so condensed, they form valuable oils.

The material in the preheaters 16 and 17 105 is delivered to the still 15 through the pipes 57 and is progressively passed through the stills 14 and 13. In its passage it is subjected to increasing temperatures and its volatile contents are distilled. Due to the presence of solids in the material in the stills, it is necessary to utilize the scrapers 60 to pull this material to the anterior end of each still so that it can be dumped.

I prefer to blow the vapors from all the stills 13, 14 and 15 through the main 55 into 110 the preheaters 16 and 17. These preheaters are alternately charged with raw and ligneous material, one being charged while the other is receiving steam and vapor.

115 In practice I use a plurality of sets of apparatus as shown, one battery of boilers and one turbine serving to operate all these sets. The pipe 96 would then be branched as shown at 91, and fed with steam and other vapors from other preheaters.

120 In practice I find that it is possible to produce valuable volatile vapors in the stills and preheaters if they are charged with suitable mixtures of raw and ligneous material. The ligneous material apparently 125 acts as a catalyst, helping to break up the 130

raw material into solids or semi-solids and volatiles. The ligneous material may be in very wet form when it enters the preheaters 16 and 17, being dried therein, and the 5 water contained therein being converted into steam. This steam, together with all other steam and vapors entering or formed in the preheaters 16 and 17, is delivered to the steam turbine 18, where it does useful 10 work, the valuable products carried therein being separated and recovered in the separator 20.

By mixing a suitable liquid, for example asphalt oil, with the ligneous material, I 15 am also able to deliver a very valuable material through the pipe 67. The characteristics of this material can be varied by changing the method of operation of the apparatus, but in general it consists of carbonized material which may contain sufficient tarry residue to permit of its being readily briquetted. This material forms a 20 valuable fuel, high in thermal value, and substantially smokeless.

25 I claim as my invention:

1. An apparatus for distillation comprising: walls forming a preheating chamber; means for passing raw material into said preheating chamber; walls forming a vaporizing chamber; means for passing material from said preheating chamber into said vaporizing chamber; walls forming a heating channel, a portion of said walls being in thermal contact with the material in 30 said vaporizing chamber; means for passing hot vapors through said heating channel; 35

nel, said vapors being at a sufficient temperature to produce a vaporized product from the material in said vaporizing chamber; means for passing the vapors after 40 they leave said heating channel into the raw material in said preheating chamber; and means for utilizing vapors from said preheating chamber in the production of power. 45

2. An apparatus for distillation comprising: walls forming a preheating chamber; means for passing raw material into said preheating chamber; walls forming a vaporizing chamber; means for passing material from said preheating chamber into 50 said vaporizing chamber; walls forming a heating channel, a portion of said walls being in thermal contact with the material in said vaporizing chamber; means for passing hot vapors through said heating channel, said vapors being at a sufficient temperature to produce a vaporized product from the material in said vaporizing chamber; means for passing the vapors after 55 they leave said heating channel into the raw material in said preheating chamber; means for injecting the vaporized product, produced in said vaporizing chamber, into the raw material in said preheating chamber; and means for utilizing vapors from 60 said preheating chamber in the production of power. 65

In testimony whereof, I have hereunto set my hand at Los Angeles, California, this 70 8th day of November, 1923.

MILON J. TRUMBLE.
